UNITED STATES PATENT OFFICE.

NATHAN T. DUNDORE, HENRY H. SECHRIST, AND ISAAC M. BRUBAKER,
OF DUNDORE, PENNSYLVANIA.

CAR-COUPING.

SPECIFICATION forming part of Letters Patent No. 359,963, dated March 22, 1887.

Application filed January 4, 1887. Serial No. 223,393. (No model.)

To all whom it may concern:

Be it known that we, NATHAN T. DUNDORE, HENRY H. SECHRIST, and ISAAC M. BRUBAKER, all of Dundore, in the county of Snyder 5 and State of Pennsylvania, have invented a new and Improved Car-Coupling, of which the following is a full, clear, and exact description.

Our invention relates to car-couplings, and 10 has for its object to provide a simple, inexpensive, and efficient coupling which will automatically couple high or low cars on straight or curved tracks, and may be adjusted so as not to couple, and which may be operated 15 without requiring the train-men to go between the cars and expose themselves to injury. The coupling has no springs or other delicate parts, and is strong and durable.

The invention consists in certain novel features of construction and combinations of parts of the car-coupling, all as hereinafter 20 fully described and claimed.

Reference is to be had to the accompanying drawings, forming a part of this specification, 25 in which similar letters of reference indicate corresponding parts in all the figures.

Figure 1 is a vertical sectional elevation of the end parts of two adjacent cars fitted with our improved couplings, with the parts ready 30 for coupling as the cars come together. Fig. 2 is an elevation of parts of the end of a car with our coupling applied thereto and with the link in cross-section, and Fig. 3 is a detail end elevation with parts in vertical section on 35 the line $\alpha\alpha$ of Fig. 1.

The draw-head A of our coupling is held to the car-body B by a suitable strap iron or irons, b, and guides, allowing the draw-head to slide longitudinally of the car, and the 40 draw-bar C, fitted to the head A, is provided with buffer and draw springs c c', arranged in the usual manner. The draw-head is provided with a flaring mouth, a, which opens 45 into the lower part, d, of a T-shaped cavity, D, formed in the draw-head, said part d forming, with the upper part, d', the front portion or head of the cavity, the rear part, d'', of which ranges backward about at the vertical center of the draw-head. The part d of the 50 cavity D forms a socket to receive the end of

the coupling-link E, and the floor 1 of said part d inclines or slopes backward, whereby the end e of the link when pressed to said floor 1 by a dead weight or block, F, held in the cavity D of the draw-head, will cause the 55 outer end, e', of the link to be raised above a horizontal position, to facilitate its entrance into an opposing draw-head. The shoulder 2 at the back of the portion d of cavity D limits the inward movement of the end of the entered link, and both the floor 1 and shoulder 2 are recessed or slotted centrally at 3, to allow free movement of the lower end or stem, g, of the coupling-pin support and tripper G, which also is fitted in the cavity D of the 65 draw-head, as presently described.

The dead-block F is made with a top plate or portion, f, two side parts, f' f', connected thereto and ranging vertically, said parts f' f' having play in the front portions, d' d, of the 70 draw-head cavity D, and a tail-piece, f'', which has play in the rear part, d'', of said cavity, and is connected with the side parts, f', of the block, which latter parts are adapted to fall upon the top of the link E when in the socket 75 d, as shown at the left-hand draw-head in Fig. 1 of the drawings, the tail-piece f'' of the block then resting on the floor of the rear part, d'', of the draw-head cavity.

The coupling-pin support and tripper G is 80 pivoted at g' at the upper ends of its side parts, g', to the opposite side walls of the draw-head A, said parts g' ranging outside of the head portion f of the dead-block F and inside of the sides f' f' of said block, whereby the 85 pin-support and the block mutually guide each other in their movements. The parts g' of the support G are fixed to a horizontally-ranging portion or shelf, g'', which forms the support proper, onto which the coupling-pin 90 H will be held up, ready for coupling, as presently explained.

The coupling-pin H is fitted to slide through a hole or holes, h, made in the draw-head, a central lug, a', being provided to afford an 95 intermediate bearing and guide for the pin just over the shelf or rest g'' of the pin-support G. The coupling pin also passes through a hole in the top plate, f, of the dead-block F, said hole having side enlargements, h', which 100

admit passage of lugs I on the pin below the plate f, and whereby when the pin is turned the lugs I, or equivalent shoulders of any suitable shape, on the pin will be under the plate 5 f, to cause the dead weight or block F to be raised bodily by the lugs as the pin H is fully raised, and preferably by devices next described.

A forked link, J, pivotally connected to the 10 coupling-pin, is pivoted to the outer end of a lever, K, which is pivoted at k to the car-body B, and has pivoted to it at l one end of a link, L, the other end of which is provided with a pin, M, which enters a segmental slot, n, at the 15 end of the short arm n' of a lever, N, which is pivoted to the car-body at n² and extends to the side of the car. The long arm n³ of the lever N projects through a long keeper, O, fixed to the car-body, and a stop-latch, P, 20 pivoted to the keeper near its upper end, has a shoulder, p, which may be swung freely outward by the rising lever N, but will drop back under the lever to hold its outer end raised, as in Fig. 2 of the drawings. The weight of 25 the long arm n³ of the lever N is sufficient to lift the coupling-pin H and the dead-block F, suspended by the lugs I on the pin, and to certainly accomplish this result the lever may have a counter-weight, n⁴, fixed to its long 30 arm, as indicated in dotted lines in Fig. 2 of the drawings.

The operation is as follows: When the levers N of the couplings of two opposing cars are not held by their catches P, the coupling-pins and dead-weights or blocks H F of both cars will be lifted by the levers and the cars will not couple when run together, and this same result will be accomplished if the link E be held by the lowered pin H and dead-block F of one car while the pin and block of the adjacent car are held up by the gravity of the lever N connected to them. When the link E is held by its end e in the draw-head of one car, as shown at the left hand in Fig. 1, 40 the stem g of the pin-tripper G lies in the recess 3, behind the draw-head shoulder 2, to prevent damage of it by the link. When the link E is held by its end e in the draw-head of one car, as shown at the left hand in Fig. 1, 45 the stem g of the pin-tripper G lies in the recess 3, behind the draw-head shoulder 2, to prevent damage of it by the link. To prepare the cars for coupling the lever N of one car will be tripped from its catch P and will lift 50 the coupling-pin H and dead-block F, and the pin-support G will swing forward to carry its shelf g² under the end of the pin. The lever N will now be lifted and caught onto the latch P, leaving the pin H and the dead-block F 55 supported on the shelf g² of the tripper G, the stem g of which then stands at the throat of the link-receiving socket of the draw-head. The slot n in the lever N allows play of the short arm of the lever on the pin N of the link 60 K, permitting the lever to be raised onto the latch P, while the coupling-pin and block H F are raised and allow free fall of the pin and block, when the shelf of the tripper is carried backward from under the pin by the entrance 65 of the end e' of the link E into the draw-head by contact of the link with the stem g of the tripper, whereupon the dead-block F falls onto

the link and the pin H falls through the link to effect the coupling of the cars about as the bumpers A' of the two couplings come in contact. To uncouple the cars the latch P of either car will be tripped from under its lever N, which then will fall to lift the connected coupling-pin and dead-block, leaving one end of the link free to allow the cars to be drawn apart. It is obvious that a car having our improved coupling may be coupled to a car provided with the ordinary link-and-pin coupling, and cars having draw-heads of different heights may readily be coupled with our couplings either on a straight track or on curves. Furthermore, there are no spring or other delicate parts to our coupling, making it very reliable and effective under any service to which it may be subjected, and the train-men need not go between the cars and expose themselves to injury.

Having thus described our invention, what we claim as new, and desire to secure by Letters Patent, is—

1. In a car-coupling, the combination, with the draw-head A, recessed at D, of a dead weight or block fitted loosely in the draw-head, and a coupling-pin, H, provided with lugs, as I, adapted to lift the block when the pin is lifted, substantially as described, for the purposes set forth.

2. In a car-coupling, the combination, with the draw-head recessed at D, of a dead weight or block fitted loosely therein, a coupling-pin, H, provided with lugs, as I, adapted to lift the block when the pin is lifted, and a gravitating pin-support pivoted to the draw-head and provided with a shelf, as g², onto which the lifted pin may rest, substantially as described, for the purposes set forth.

3. In a car-coupling, the combination, with the draw-head recessed at D, of a dead weight or block fitted loosely therein, a coupling-pin, H, provided with lugs, as I, adapted to lift the block when the pin is lifted, and a gravitating pin support and tripper pivoted to the draw-head and provided with a shelf, as g², onto which the lifted pin may rest, and a stem, g, at the mouth of the link-socket, substantially as described, for the purposes set forth.

4. In a car-coupling, the combination, with the draw-head, a dead-block fitted loosely therein, and a coupling-pin having lugs, as I, adapted to lift the block when the pin is lifted, 120 of a lever, as N, fulcrumed to the car, and connections, substantially as described, from said lever to the coupling-pin, whereby the weight of the lever will overbalance that of the coupling-pin and dead-block and hold them up to 125 prevent coupling of the car, as set forth.

5. In a car-coupling, the combination, with the draw-head, a dead-block fitted loosely therein, and a coupling-pin having lugs, as I, adapted to lift the block when the pin is lifted, 130 of a gravitating tripper, G, having a shelf, g², adapted to support the pin and block, a lever, as N, fulcrumed to the car-body, and connections from said lever to the coupling-pin, sub-

stantially as described, whereby the weight of the lever will overbalance that of the coupling-pin and dead-block to lift them and the tripper, G will swing under the pin to support it 5 and the dead-block, as set forth.

6. In a car-coupling, the combination, with the draw-head, A, recessed at D, a dead-block, F, a pin, H, having lugs I, a gravitating pin support and tripper, G, all constructed and arranged for operation substantially as specified, of a lever, N, fulcrumed to the car-body and provided with a slot, n, and connections L K J, between the lever and coupling-pin, substantially as shown and described.

15 7. In a car-coupling, the combination, with the draw-head, A, recessed at D, a dead-block, F, a pin, H, having lugs I, and a gravitating pin support and tripper, G, adapted to hold up the pin and dead-block, of a lever, N, fulcrumed to the car-body, connections from said 20 lever to the coupling-pin whereby the lever

normally lifts the pin and dead-block, and a latch, P, on the car-body, adapted to support the outer end of the lever to prevent fall of the coupling-pin and block, substantially as described, for the purposes set forth.

8. A car-coupling constructed substantially as herein shown and described, and comprising a draw-head, A, recessed at D, a dead-block, F, fitted in said recess, a gravitating pin support and tripper, G, a coupling-pin, H, having lugs, as I, adapted to support the block F, a lever, N, fulcrumed on the car, connections J K L M between the lever and coupling-pin, and a latch, P, on the car, all arranged for operation as and for the purposes set forth.
